MEAT FEED ATTACHMENT FOR PORTION CONTROL IN A MOLDING MACHINE

Bernard Miles, 285 Vermont Ave.,
Irvington, N.J. 07111

Filed Mar. 30, 1972, Ser. No. 239,855

Term of patent 14 years

Int. Cl. D15—08

U.S. Cl. D55—1 B

FIG. 1

FIG. 2

FIG. 3

FIG. 4

FIG. 5

FIG. 1 is a front elevational view of a meat feed attachment for portion control in a molding machine, showing my new design.

FIG. 2 is a top plan view thereof.

FIG. 3 is a rear elevational view thereof.

FIG. 4 is a bottom plan view thereof.

FIG. 5 is a perspective view from the lower rear thereof.
I claim:

The ornamental design for a meat feed attachment for portion control in a molding machine, as shown and described.
